W. W. Williamson

Atty.

UNITED STATES PATENT OFFICE.

WILBER W. EVERTS, OF ROCHESTER, NEW YORK.

METHOD AND MEANS FOR CLEANING SILVER, GOLD, PLATINUM, AND OTHER ARTICLES.

1,416,403.

Specification of Letters Patent. Patented May 16, 1922.

Application filed July 6, 1918. Serial No. 243,732.

To all whom it may concern:

Be it known that I, WILBER W. EVERTS, a citizen of the United States, residing at Rochester, in the county of Monroe and 5 State of New York, have invented new and useful Improvements in Methods and Means for Cleansing Silver, Gold, Platinum, and Other Articles, of which the following is a specification.

0 My invention relates to new and useful improvements in method of and means for cleaning silver, gold, platinum, and other articles and has for its object to provide a plate or unit of two metals adapted to be 5 submerged in a salt solution whereby the local action set up by plate or unit will decompose the solution and free the chlorine, which will destroy the foreign matter on the surfaces of metallic and other articles immersed in the solution.

A further object of the invention is to provide a bi-metal plate or unit, which when placed in a salt solution will set up an action to decompose the solution for freeing the 5 chlorine to act as a cleaning agent.

Another object of the invention is to provide a plate or unit composed of zinc and copper either as an alloy or laminated structure.

0 With these ends in view this invention consists in the details of construction and combination of elements hereinafter set forth then specifically designated by the claims.

5 In order that those skilled in the art to which this invention appertains may understand how to make and use the same I will describe its construction in detail referring by numeral to the accompanying drawing 0 forming a part of this application in which—

Fig. 1, is a sectional view of a receptacle or container adapted to hold a salt solution in which my improved plate or unit is submerged and in which the articles to be cleaned are immersed.

Fig. 2, is a sectional view of a slightly modified form of plate or unit.

Fig. 3, is a similar view of a further modified form of plate or unit.

Fig. 4, is a sectional view of another form of my invention; and

Fig. 5, is a similar view of a still further construction of my improved plate or unit.

5 In carrying out my invention as here em-

bodied 2 represents a suitable receptacle or container for holding a salt solution 3 formed by mixing salt with water in any desirable proportions and in this solution is submerged the plate or unit 4.

The plate or unit is formed of zinc and copper preferably in the form of an alloy in which zinc is predominant as for instance said plate may contain 75% of zinc and 25% of copper.

Instead of making the plate or unit as an alloy it may be formed as a laminated structure each metal being in the form of a plate or sheet shown in Figs. 2 to 5 inclusive fastened together in any suitable or well known manner. The plate or unit when made as a laminated structure comprises a sheet of zinc 5 and a sheet of copper 6 one of which is superimposed upon the other.

In Fig. 2, the two sheets of metal are 75 shown as adhering to each other which may be accomplished by the well known method of rolling, while in Fig. 3, one of the sheets, as for instance the copper sheet 6, is shown with its edges turned up or bent over the 80 edges of the other sheet 5 so as to form a flange 7 which will readily hold the two sheets in contact with one another.

In Fig. 4, I have shown another means whereby the two sheets may be fixed to each 85 other and comprises a number of rivets passing through both sheets and having their ends headed against the outer faces of said sheets and these rivets would preferably be of copper.

Another way to fasten the two sheets together would be to form holes in one of the sheets, as for instance the zinc sheet 5, and then draw portions of the other sheet through said holes which would produce 95 lugs 9 and then expand or enlarge the projecting ends of said lugs so as to form heads which would prevent the separation of the sheets.

In practice the salt solution is placed in a 100 suitable receptacle and my improved cleaning plate or unit is submerged therein after which the articles to be cleaned are immersed in the solution so that at least one of them is in contact with each other at 105 which time an action is set up to decompose the salt solution and separate the chlorine which will destroy the foreign matter on the surfaces of the articles thereby thoroughly cleaning them. After the articles have been 110

immersed a sufficient length of time they are rinsed and wiped leaving them perfectly clean and giving them a very bright luster.

Of course I do not wish to be limited to 5 the exact details of construction as herein shown as these may be varied within the limits of the appended claims without departing from the spirit of my invention.

Having thus fully described my invention, 10 what I claim as new and useful—

1. The method of cleaning the surface of an article which consists in immersing the article in a salt solution containing a bi-metal plate.

15 2. The method of cleaning the surface of an article which consists in immersing the

article in a salt solution containing a plate of two metals of opposite polarity.

3. As an article of manufacture, a unit comprising a sheet of zinc, a sheet of copper 20 and rivets passing through both of said sheets for fastening them together.

4. An article of manufacture, a unit comprising two sheets of metal of opposite polarity, one of said sheets having holes there- 25 through and lugs drawn from the other sheet, passing through said holes and headed to hold the sheets together.

In testimony whereof, I have hereunto affixed my signature.

WILBER W. EVERTS.
